(57) CLAIM

The ornamental design for footwear, as shown and described.

DESCRIPTION

FIG. 1 is a front perspective view of the footwear according to the design;

FIG. 2 is a rear view thereof;

FIG. 3 is a right side view thereof;

FIG. 4 is a left side view thereof;

FIG. 5 is a top view thereof; and,

FIG. 6 is a bottom plan view thereof.

The broken lines on the surface of the shoe represent stitching and form a part of the claimed design. The broken lines at the sole of the shoe form no part of the claimed design. The contrasting shading used in the drawings depicts a contrasting appearance.
